UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAILWAY-TRACK IMPLEMENT.

Application filed September 27, 1923, Serial No. 665,121. Renewed May 16, 1925.

To all whom it may concern:

Be it known that I, HAROLD G. WARR, a citizen of the United States, residing at Park Ridge, in the county of Cook and 5 State of Illinois, have invented certain new and useful Improvements in Railway-Track Implements, of which the following is a specification.

My invention relates to railway track implements, and more particularly to a tool 10 for expediting the removal of rail anchoring devices from a rail.

The primary object of the invention is to provide an improved track implement 15 adapted to be used in connection with the removal of rail anchors, whereby rail anchors may be easily removed from their rail gripping position with a minimum of labor, and without danger of subjecting the 20 anchors to excessive distortion, or otherwise damaging them to such extent as would make them unsuitable for further use.

A more specific object of the invention is to provide an implement of the above character, which is particularly suitable for removing rail anchors of the type comprising a rail base embracing yoke having hook-shaped jaws for engaging the upper inclined surface of the rail base, and means for bearing against the under surface of the base, which yoke may be applied by first hooking 30 one of said jaws over one edge of the rail base, and then forcing the other jaw upon the other edge of the rail base by driving 35 the anchor in the direction of its length, until the jaws and body of the anchor are distorted sufficiently to exert a firm spring grip of the device on the rail.

In rail anchors of this general type, it is 40 desirable to provide the jaw that is first hooked over the rail with a shoulder, or other form of abutment, which engages the edge of the rail when the anchor is in its applied position, so as to resist any tendency 45 that the anchor may have to move transversely of the rail in the direction from which it was driven. In some constructions, this abutment takes the form of an abrupt shoulder, and in other constructions it is 50 formed by means of a bend in the jaw. While such abutments are desirable to maintain the anchors in their applied positions, they make it difficult to remove the anchors.

Prior to my invention it has been the 55 practice, in removing rail anchors of the

above type from a rail, to insert a crow-bar under the abutment end of the anchor and spring it upward until the abutment clears the upper edge of the rail base, and then strike the curved end of the anchor with a 60 sledge to drive it transversely of the rail to remove the other jaw from its gripping contact with the other edge of the rail base. This practice is objectionable for the reason that the workmen, using the crow-bars, do 65 not always use sufficient care to prevent excessive distortion of the anchor. It is also difficult, regardless of the care exercised by the workmen, to apply the exact amount of power to flex the anchor to such extent 70 only as will permit the abutment to clear the upper edge of the rail base. When such abutment, instead of being in the form of an abrupt shoulder, is formed by bending the jaw so that the portion beyond the edge 75 of the rail has a greater angle than the inclined surface of the rail base, the workmen sometimes, failing to locate a convenient fulcrum for the crow-bar, omit its use, and remove the anchor by striking the curved 80 portion of the jaw with a sledge. In such case the hammer blows against the curved end of the yoke must be of such force as will overcome the resistance of the abutment. Such force usually results in so expanding the jaw that the anchor is unsuit- 85 able for further use.

One of the specific objects of my invention is to overcome the above-mentioned and other incidental objections by providing a 90 simple and inexpensive implement for flexing the abutment ends of rail anchors of the above or similar character, which flexing will be limited to such degree only as will be sufficient to permit the said abutment of 95 the anchor jaw to clear the upper edge of the rail base.

The invention has for further objects the new and improved constructions relating to track implements as will be hereinafter described and claimed, for carrying out the above stated objects, and such other objects as will appear from the following description.

A preferred embodiment of my invention 105 is illustrated in the accompanying drawing, wherein like characters of reference designate corresponding parts in the three figures of the drawing, and wherein—

Fig. 1 is a side view in elevation of my 110

improved track implement, showing the same in the position in which it is placed when removing a rail anchor from the base flange of a rail, the said anchor being shown 5 in elevation and the rail in cross-section;

Fig. 2 is an edge view in elevation, of the track implement shown in Fig. 1, the rail anchor in this figure being shown in section; and

10 Fig. 3 is a view in perspective of the track implement.

Referring to the drawing:

15 10 designates a railroad rail, 11 one of the cross-ties on which the rail is supported, and 12 designates generally a rail anchor of a well-known one-piece type, applied in its operative position on the base flange of a rail. My improved track implement is shown, and will be described in connection 20 with the one-piece yoke type of anchor, such type of anchor, however, being shown only for the purpose of illustrating certain features of my invention. It will, therefore, be obvious to those familiar with the art to 25 which my invention appertains, that the improved track implement hereinafter described, may be used to an advantage in removing rail anchors of various types and constructions from their applied position. 30 It will also be apparent that the utility of the implement is not confined to the removal of anchoring devices, but, if desired, may be used to expedite the application of rail anchors to their applied position on a rail, 35 or employed in other analogous situations.

The rail anchor herein shown consists of a relatively heavy bar of steel, having its ends bent upward to form hook-shaped jaws 13 and 14 for engaging opposite edges of the 40 rail base, and with its body bent upward to provide a seat 15 which bears against the under surface of said base. The jaw 14 is somewhat longer than the jaw 13, so as to provide sufficient clearance to permit the 45 anchor to be readily applied to its initial position on the rail. The anchor is applied to its initial position by first hooking the jaw 14 over one edge of the rail base, and then swinging the jaw 13 upwards until its 50 tapered end 16 projects over the other edge of the rail base. The anchor may then be driven transversely of the rail to force the jaw 13 and seat 15 into tight gripping contact with the upper and lower surfaces, 55 respectively, of the rail base. The jaw 14 of anchoring devices of the above type is ordinarily provided with a shoulder 17 or other suitable form of abutment adapted, when the anchor is in its applied position, to bear 60 against one edge of the rail base so as to resist any tendency that the anchor may have to move transversely of the rail, in the direction from which it was driven.

When it is desired to remove the anchor, 65 the jaw portion 14 of the anchor is flexed

upwardly until the shoulder 17 clears the upper edge of the rail base, and the anchor is then driven in the direction of its length transversely of the rail, until the jaw 13 is disengaged from the other edge of the 70 rail base. A flexing or distorting of the jaw portion 14 is preferably accomplished by means of my improved track implement which consists preferably of a handle 18, which may be made of any desirable length, 75 formed at one end with a foot 19 formed with a bearing point 20 adapted to fulcrum upon the upper surface of the rail base, and provided at its extremity with a lateral projection or stud 21, adapted to extend 80 under the jaw 14 of the anchor.

It will be seen that by rocking the handle of the implement toward the ball of the rail, the foot 19 being fulcrumed at 20 on the upper surface of the rail base, force 85 will be exerted against the under surface of the jaw 14 to flex the jaw and body portions 12 of the anchor upwardly to permit the shoulder 17 of the jaw to clear the upper edge of the rail base. In order to avoid 90 subjecting the jaw portion 14 of the anchor to excessive distortion, I preferably provide the foot of the implement with a stop 22 to limit the rocking movement of the foot 19 on its pivot 20 so as to confine the flexing 95 of the jaw 14 to such an amount as will permit the shoulder 17 to clear the upper edge of the rail base. The handle 18 is, preferably, offset at 18^a laterally of the foot in a direction opposite to that of the 100 stud 21. With such construction it will be seen that the stud 21 and handle 18 are disposed longitudinally of the rail on opposite sides of the fulcrum 20, whereby the implement may be conveniently balanced when 105 stressing the anchor.

While I have shown and described my invention in connection with one specific embodiment, it will be obvious that modifications in structure might be made without 110 departure from the spirit of my invention. I therefore wish it understood that I do not limit myself to the specific structure shown and described, except in so far as specific limitations appear in the appended 115 claims.

I claim:

1. An implement for use in removing rail anchors comprising a bar having anchor engaging means and formed with an angular 120 portion providing a fulcrum to bear against the upper surface of the rail base and on which said bar is adapted to rock and with means for limiting said rocking movement.

2. An implement of the character described, comprising a bar having a handle portion and formed with a portion at an angle thereto adapted to engage with a rail anchor device and formed with means providing a fulcrum for said bar, whereby rock- 125 130

ing of said bar on said fulcrum will raise said rail anchor, and means providing a stop to limit said rocking movement of said bar.

5. 3. An implement of the character described, comprising a bar formed at one end with a foot having a lateral projection adapted to engage with a rail anchor, and formed with a portion adapted to bear 10 against the base flange of a railroad rail to provide a fulcrum on which said foot is rocked to apply force to said rail anchor, said foot being formed with a stop adapted to engage with the rail base to limit said 15 rocking movement.

4. A device for removing a rail anchor, comprising a bar having a handle portion and formed with a portion at an angle thereto to engage said anchor and provided 20 with a fulcrum adapted to bear against the base flange of the rail at one side of the anchor, whereby rocking of said bar will subject said rail anchor to a flexing stress.

5. A device for removing rail anchors

comprising a bar having a handle portion 25 formed with a portion at an angle thereto adapted to project under a portion of an anchor, a projection on said angular portion to provide a fulcrum adapted to bear against the base flange of the rail, whereby rocking 30 of said bar will subject said rail anchor to a flexing stress.

6. An implement of the character described comprising a bar having a handle portion and formed at one end with a foot 35 having a lateral projection adapted to engage with a rail anchor, and formed with a portion adapted to bear against the base flange of a railroad rail to provide a fulcrum on which said foot is rocked to apply 40 force to said rail anchor, said foot being formed with a projection adapted to engage with the rail base to limit said rocking movement and said handle portion being offset laterally of said foot in a direction 45 opposite to that of the anchor engaging portion.

HAROLD G. WARR.
